By his Attorneys William N. Davis

Blackburn, Spencer & Clark.

UNITED STATES PATENT OFFICE.

WILLIAM N. DAVIS, OF DETROIT, MICHIGAN, ASSIGNOR TO GENERAL MOTORS CORPORATION, OF DETROIT, MICHIGAN, A CORPORATION OF DELAWARE.

COWL VENTILATOR.

Application filed June 7, 1924. Serial No. 718,540.

To all whom it may concern:

Be it known that I, WILLIAM N. DAVIS, a citizen of the United States, and a resident of Detroit, county of Wayne, and State of Michigan, have invented certain new and useful Improvements in Cowl Ventilators, of which the following is a full, clear, concise, and exact description, such as will enable others skilled in the art to 10 which the invention relates to make and use the same, reference being made therein to the accompanying drawings, which form a part of this specification.

This invention relates to cowl ventilators, and has for an object the provision of a ventilator with a sealing strip which can be readily assembled, and which will form a rain-tight joint for the ventilator proper. In one desirable arrangement, the 15 flexible material of the sealing strip is held by a metal binder grasping its lower edge, the binder fitting frictionally about the wall of the drainage channel surrounding the ventilator opening, and the flexible material projecting above the wall of the channel for yielding engagement with the ventilator.

The above and other objects and features of the invention will be apparent from the 20 following description of one illustrative embodiment shown in the accompanying drawings, in which:

Figure 1 is a side elevation of an automobile embodying one of the described cowl 25 ventilators;

Figure 2 is a side view on a larger scale of part of the cowl, broken away to show the ventilator in vertical section; and

Figure 3 is a top plan view of the ventilator, partly broken away.

For purposes of illustration, the ventilator is shown in the cowl 10 of an automobile 12. The cowl is provided with a 30 ventilator opening having a down-turned edge 14 supporting a drainage channel 16 communicating with a drainage pipe 18. The ventilator opening may be closed when

desired by a swinging ventilator 20 having a down-turned flange 22 entering channel 16, the lower position of the ventilator being determined by rubber stops 24 on brackets 26 carried by the channel 16. Ventilator 20 is secured by screws 28, or in any other desired manner to a stamping 30 bolted to a U-shaped operating member 32 35 having arms 34 pivoted on a bolt or bolts 36. The ventilator is operated by an arm 38, and is held in any desired position by a ratchet 40 yieldingly operated by a spring 42.

In order to make the ventilator rain tight when closed, I provide a sealing strip comprising an annular piece 44 of flexible material such as felt or rubber, grasped at its lower edge by a metal binder 46, shown 45 as U-shaped in cross-section. The sealing strip is arranged with the binder 46 encircling and frictionally engaging the inner wall of channel 16, and with the flexible material 44 yieldingly engaging the swing- 50 55 60 65 70 75 80 85 90 95 ventilator 30 when closed.

While one illustrative embodiment of the invention has been described in detail, it is not my intention to limit its scope to that particular embodiment, or otherwise than by the terms of the appended claim.

I claim:

A cowl ventilator comprising, in combination, a cowl having a ventilator opening with a channel about its edge, a swinging ventilator for the opening, and a sealing strip in the channel, the sealing strip including an annular piece of flexible material, and a metal binder U-shaped in cross-section grasping the lower edge of the annular piece and fitting snugly around the inner wall of said channel, with the flexible material projecting above said wall for yielding engagement with the swinging ventilator.

In testimony whereof I affix my signature.

WILLIAM N. DAVIS.
